THEODOR LANGER, DECEASED, LATE OF VIENNA, AUSTRIA, BY OSKAR GOLD, OF VIENNA, AUSTRIA, ADMINISTRATOR, ASSIGNOR TO LANGER FUEL SAVING CORPORATION OF AMERICA, OF WILMINGTON, DELAWARE

TOP-AIR-SUPPLYING APPARATUS FOR FURNACES

Application filed February 6, 1929, Serial No. 337,935, and in Austria February 8, 1928.

The invention relates to top air supplying apparatus for furnaces more particularly for furnaces for locomotives, stationary steam generating plants and the like.

5 It has heretofore been proposed to provide the fire door opening with horizontal ribs for the dual purpose of heating the top air entering through the fire door and cooling the fire door itself. However, this construction has not proved successful since the 10 heating of the top air is too slight and the burning of the door or the door plate is not efficiently prevented.

To avoid these disadvantages the present 15 invention has been devised. In this invention the furnace door is provided with an opening in which, several cooling ribs are horizontally and exchangeably mounted, one of these ribs being arranged in the furnace 20 chamber parallel to the door plate, in order to partly deflect the top air along the door plate.

In the annexed drawing a constructional 25 form of the subject matter of the invention is shown by way of example.

Fig. 1 shows the fire door in front elevation, Fig. 2 is a vertical central section thereof, taken on line 2—2 of Fig. 1 and Fig. 3 is a side elevation of the same.

30 Referring to the drawing, a substantially circular door 1 is mounted on a hinge 2 which may be secured to a furnace (not shown), and may have hinge pivot pins 2^a about which the door may swing. The door has a central 35 aperture 3 over which fits a substantially rectangular cap having its bottom side open but adapted to be closed by a pivotally mounted rocking plate 14. In order to secure the cap to the door, the cap is made with flanges 40 18 projecting laterally from the opposite vertical sides of the cap. The flanges lie flat against the face of the door and bolts 17 pass through them securing the cap to the door.

To mount the rocking plate 14, centrally 45 bored bosses 3^b are formed integrally with the cap 3^a at its lower corners and projecting down slightly therefrom. Holding the rocking plate 14 and adapted to rotate within the bosses 3^b are pivot members 8, 8^a, each having 50 a central rod portion and a flattened end por-

tion, the end portion projecting out of the boss and being slotted to accommodate the edges of the rocking plate, which edges are held in the slots by screw bolts 8^b.

The other end of the pivot member 8, projects from the boss and has a weighted arm or lever 9 secured thereon by set screw 9^a, in such a position that when the arm is just above horizontal position (see dotted line position of Fig. 3) the rocking plate is vertical and the bottom side of the cap 3^a is open allowing top air to enter the furnace through the door opening 3. When the arm is rotated 90° clockwise to just past vertical (see full line position Fig. 3) the rocking plate is vertical and the air passage in the bottom side of the cap is closed. Pins 10 and 11 are provided to hold the weighted arm from moving past the positions just described, it being apparent that the force of gravity acting on the arm will hold the arm against the pins and therefore in the positions described.

In order to heat the top air as it passes through the door aperture 3 into the furnace, 75 parallel ribs 19 are provided, and in order to protect the door against burning at the bottom, there is provided a horizontal rib 6 below and parallel to ribs 19. The ribs 19 extend through the aperture 3 into the 80 furnace and are provided with eyes 5 by which they may be mounted one above the other in horizontally parallel relation on two vertically parallel bolts 4 which pass down through and are secured to the top side of the 85 cap 3^a near the side edges thereof. Rib 6 is mounted below the ribs 19 on the bolts 4 in the same manner as ribs 19 but rib 6 has an apron 6^a which projects downwardly parallel to but spaced from the inside of the door 1. 90 To insure the maintenance of this spacing a centrally located lug 7 projects from the apron toward the inside of the furnace door.

From the foregoing it will be apparent that when the plate 14 is vertical, air is permitted, 95 to enter the furnace, coming into the cap 3^a and passing therefrom between the ribs 19 and through the door aperture 3, some of the air passing under the rib 6 and down between the door 1 and rib 6. Thereby the incoming, 100

air is heated and the lower portion of the door is protected against burning.

What is claimed is:

1. The combination comprising a furnace door having an aperture therein, a plurality of ribs, supported by said door and projecting through said aperture, one of said ribs having a downwardly projecting portion spaced from but parallel to said door, whereby to cause air passing through said aperture to be deflected downwardly between said portion and the door.
2. The combination comprising a furnace door having an aperture therein, a cap outside of said door and secured thereto and covering said aperture, the bottom side of said cap being open, means to close said bottom side at will, a plurality of removable ribs secured to said cap and extending through said aperture, one of said ribs having a laterally projecting portion spaced from but parallel to said door whereby to cause air passing through said aperture to be deflected between said portion and the door.
3. Apparatus for supplying top air to a furnace comprising a fire door, a central opening in said fire door, a plurality of substantially horizontal exchangeable cooling ribs projecting inwards, at least one of said cooling ribs being bent parallel to and covering part of the inside of the fire door, the bent part of said bent cooling rib being spaced from the inside of the fire door.

In testimony whereof I have affixed my signature.

OSKAR GOLD,
*Administrator of Estate of Theodor Langer,
Deceased.*
